UNITED STATES PATENT OFFICE.

JAMES STANWOOD PIERCE, OF TACOMA, WASHINGTON.

CEMENT BLOCK.

No. 872,364.

Specification of Letters Patent.

Patented Dec. 3, 1907.

Application filed September 24, 1906. Serial No. 335,987.

To all whom it may concern:

Be it known that I, JAMES STANWOOD PIERCE, citizen of the United States, residing at Tacoma, in the county of Pierce and State 5 of Washington, have invented certain new and useful Improvements in Cement Blocks; and I do hereby declare the following to be a full, clear, and exact description of the invention, such as will enable others skilled in 10 the art to which it appertains to make and use the same.

My invention relates to new and useful improvements in wall construction, and my prime object is to construct the walls of plastic blocks and to provide suitable means for 15 securing the blocks together.

Other objects and advantages will be hereinafter referred to and more particularly pointed out in the claims.

20 In the accompanying drawings which form a part of this application, Figure 1 is a side elevation of a section of wall constructed of my improved blocks. Fig. 2 is a longitudinal vertical sectional view thereof. Fig. 3 is 25 a top plan view of the wall. Fig. 4 is a sectional view as seen from line 4—4, Fig. 1, and Fig. 5 is a perspective view of one of the blocks.

Referring to the drawings in which similar 30 reference numerals designate corresponding parts throughout the several views, 1 indicates the blocks from which the wall is constructed, said blocks being preferably composed of plastic material, such as cement or 35 the like, and when the blocks are molded they are provided upon opposite sides with grooves 2, and disposed through the blocks at the center of each of the grooves 2 are openings 3. The blocks are so arranged that 40 when they are properly assembled together, the grooves 2 of each tier will register with the grooves of the opposite tier and the openings 3 likewise register with each other when the blocks are properly assembled.

45 In constructing a wall from the form of block herein shown, the first layer of blocks are properly placed upon the ground or specially prepared foundation, after which a similar layer is disposed on top of the 50 first layer and are so arranged that the center of the blocks of the second layer is directly over the meeting end of the blocks in the lower layer, thereby breaking the joints between the several layers. Before disposing 55 the blocks of the second layer in position, a girder 4 is disposed in each of the grooves of

the several blocks and are of sufficient thickness to extend substantially half their height above the upper edge of the block, and in this manner it will be seen that when the 60 next layer of blocks is disposed in position on the first layer, that the girder will be entirely inclosed between the two grooves.

As best shown in Figs. 3 and 4, the wall 65 consists of three tiers of blocks disposed side by side, and the girders are of sufficient length to engage all three of the tiers. To more securely bind the several tiers and layers of the blocks together, I dispose a plurality of shafts 5 through the several register- 70 ing openings in the blocks. The girders 4 are also provided with openings through which the shafts also extend, thereby securely locking all of the blocks together and forming an exceedingly compact wall. When 75 the blocks are used for forming walls of buildings, a portion of the girders 4 may extend from one wall to the other, thereby forming means for supporting the floor, and as the girders 4 and shafts 5 are preferably con- 80 structed of metal, it will be seen that a building may be constructed with the use of very little lumber or other inflammable substances, thereby rendering the structure fireproof. It 85 will be seen also that this form of block together with the means for securing the same together is particularly adapted for use in building dams, sea walls and the like.

It will now be seen that I have produced a 90 cheap and durable form of block whereby the same may readily be disposed in position and permanently secured together, and one wherein the blocks may be completed with one operation of the mold.

What I claim is:

1. A wall formed of plastic blocks laid in superposed layers and each block formed with grooves upon opposite sides and openings with the grooves and openings registering girders disposed in coincident register- 100 ing grooves, and disposed transversely of the length of the blocks, there being two girders to each block, and tie shafts passed through the openings of the blocks and coincident openings in said girders, and extended at 105 right angles to the girders.

2. A wall formed of plastic blocks laid in superposed layers and each block formed with grooves upon opposite sides and openings with the grooves and openings registering girders disposed in coincident register- 110 ing grooves and disposed transversely of the

length of the blocks, there being two girders to each block, and tie shafts passed through the openings of the blocks and coincident openings in said girders and extended at 5 right angles to the girders, said blocks being laid to break joints and the girders being parallel to each other and concealed from view.

In testimony whereof I have signed my name to this specification in the presence of two subscribing witnesses.

JAMES STANWOOD PIERCE.

Witnesses:

JOHN COWAN,
EDWARD MARX.
